OPHTHALMIC MOUNTING

Filed May 20, 1926

INVENTOR.
HERMAN KATZ
BY *Joseph B. Gardner*
ATTORNEY.

UNITED STATES PATENT OFFICE

HERMAN KATZ, OF OAKLAND, CALIFORNIA

OPHTHALMIC MOUNTING

Application filed May 20, 1926. Serial No. 110,418.

My invention relates to an ophthalmic mounting, and particularly to the nose rests thereon.

An object of the invention is to provide 5 an ophthalmic frame having nose-guards which are formed integral with the lens rings and may be readily adjusted whereby the frame may be fitted to practically any size or shape of nose and without altering 10 the pupillary distance of the rings.

Another object of the invention is to provide a mounting with the foregoing advantages in which the entire frame including the rings and rests may be formed as a single integral unit.

A further feature of the invention is in the provision of nose-rests of the character described which may be incorporated with mountings both of the type in which the 20 bridge is arranged to set upon the nose and the type in which the bridge merely spans the nose.

A still further object of the invention is to provide means for reinforcing the rests and 25 the attachment between the same and the rings, which will be entirely concealed within such members.

The invention possesses other objects and 30 features of advantage, some of which, with the foregoing, will be set forth in the following description of the preferred form of my invention which is illustrated in the drawings accompanying and forming part of the specification. It is to be understood 35 that I do not limit myself to the showing made by the said drawings and description, as I may adopt variations of the preferred form within the scope of my invention as set forth in the claims.

40 Referring to said drawings:

Figure 1 is a rear elevation of an ophthalmic mounting constructed in accordance with my invention.

Figure 2 is a plan view of the mounting. 45 Figure 3 is a vertical section view of the mounting taken on the line 3-3 of Figure 1.

Figures 4 and 5 are views similar to Figures 1 and 3, except that the rests are shown 50 embodied in a mounting in which the bridge

is of the type arranged merely to span the nose.

As illustrated in the drawings, the mounting comprises a frame 2 which includes a pair of rings 3 and 4 and a bridge 5. The 55 frame, or at least the portion comprising the rings 3, is preferably formed of cellulose composition, and, as here shown, the entire frame is constructed as a single integral member. Suitable temples 6 are preferably 60 hinged to the rings at opposite ends of the frame.

Preferably formed of cellulose composition, and here shown as an integral part of the frame, are nose-rests 7 and 8 which are 65 respectively associated with and extend from the rings 3 and 4. The base portions 9 of the rests project from the rings transversely of the plane of the frame and rearwardly therefrom, and the rests as a whole extend 70 upwardly in more or less concentric relation with the associated rings. The base portions 9 and head portions 12 of the rests are preferably widened in a direction transversely of the frame so as to provide increased nose engaging surfaces for the rests, in the present form of the invention the 75 widening of the head portions being accomplished by bending the upper extremities forwardly of the frame.

In fitting the frames to the wearer, the 80 rests may be adjusted by bending same at their point of connection with the rings or any portion of their length. In this way a maximum amount of adjustment is available without entailing a change in the pupillary distance of the frame. In order to insure the rigidity of the rests, particularly 85 when the adjustment has been made, and to permit of repeated and extreme variations 90 in the adjustment of the rests, I provide means for reinforcing the rests throughout their length and at their point of connection with the rings. As here shown there is embedded in each rest a wire 13 which is 95 preferably flexible and formed of metal. The wire 13 it will be noted extends the full length of the rests and extends into and is embedded in the associated ring. The reinforcement for each of the rests may be 100

separate as shown in Figures 1 and 3, or it may be formed as one continuous member 14 which extends through the bridge, as shown in Figures 4 and 5.

5 It will now be evident that the rests may be adjusted to be positioned almost any manner desired. First the rests may be adjusted perpendicularly to the plane of the frame; second, they may be adjusted co-planar to the frame, and third, each rest may be twisted about its own axis so that the head portion as well as all the other portions of the rests may lie flat against the nose.

15 In the embodiment illustrated in Figures 4 and 5, the bridge is of the type arranged to merely span the nose, and the rests are therefore adapted to receive the full weight of the mounting. The rests of my invention are particularly advantageous in this 20 arrangement, since they may be so formed and adjusted as to lie at the front or rear of the frame or exactly between the rings.

I claim:

25 1. In an ophthalmic mounting, the combination with a frame including lens rings of cellulose composition and a bridge connecting said rings together, nose-rests of cellulose composition formed integral with said rings, and metal reinforcing means embedded in said rests and extending therefrom and embedded in said rings.

30 2. In an ophthalmic mounting, the combination with a frame including lens rings of cellulose composition and a bridge connecting said rings together, a nose-rest of cellulose material formed integral with each ring and extending transversely and upwardly therefrom at its point of connection therewith, the upper portion of said rests being 40 formed to provide a nose bearing surface of larger area transversely of the frame than that of the lower portion of the rests, and a flexible reinforcing member embedded in said rings and rests and extending respectively therein substantially concentric and longitudinally.

35 3. In an ophthalmic mounting, the combination with a frame including lens supporting portions of non-metallic composition and a bridge connecting said portions together, a nose rest of non-metallic composition formed integral with each portion and extending transversely and upwardly therefrom at its point of connection therewith, and a flexible metal reinforcing member embedded in said portions and rests and extending respectively therein substantially concentric and longitudinally.

40 4. In an ophthalmic mounting, a frame of non-metallic composition including lens holding portions, nose rests formed integral with said portions and adapted to be bent to variously shape and dispose the bearing 45 portions of the rests, and metallic reinforce-

ing members imbedded in and extending from said rests into said portions.

In testimony whereof, I have hereunto set my hand at Oakland, California, this 17 of May, 1926.

70 HERMAN KATZ.
